UNITED STATES PATENT OFFICE.

GEORGE D. WYCKOFF, OF OIL CITY, PENNSYLVANIA.

IMPROVEMENT IN APPARATUS FOR AMALGAMATING ORES AND PRECIOUS METALS.

Specification forming part of Letters Patent No. 124,873, dated March 19, 1872.

SPECIFICATION.

To all whom it may concern:

Be it known that I, GEORGE D. WYCKOFF, of Oil City, in the county of Venango and State of Pennsylvania, have invented a new and useful Improvement in Amalgamators; and I do hereby declare the following to be a full, clear, and exact description of the same, reference being had to the accompanying drawing, in which—

Figure 1 is a perspective view of my invention. Fig. 2 is a plan of the same. Fig. 3 is a longitudinal vertical section and elevation of the same.

This invention relates to that class of amalgamators wherein the agitation of the mercury and auriferous sand or earth is produced by cylinders revolving in concave troughs, from one to another of which the said sand or earth is automatically transferred in succession; and it consists, first, in providing the revolving cylinders with a covering of fibrous or equivalent material; second, in causing said cylinders to revolve in a direction opposite to the direction of the flow through the machine; third, in the adjustability of the machine in reference to a horizontal plane; fourth, in the mountings of the cylinders so that they may be readily removed; fifth, in the arrangement of the driving mechanism; sixth, in the construction whereby all of the cylinders may be removed at one operation.

That others may fully understand my invention, I will particularly describe it.

The case A, which contains the amalgamating-troughs B and agitating-rollers C, I prefer to make of cast-iron, in sections of three troughs, though any other material or proportion may be employed, if desirable or necessary. The sections of the case A are cast with vertical ends, extending below the concaves or troughs B, as shown in Fig. 3, so that when a plate, D, is bolted to the lower edges of the vertical sides a space, b, is formed between said concaves and said plate for the introduction of steam or hot water, to raise the temperature of the auriferous matters within the amalgamating-troughs, to facilitate the union of the mercury and precious metal. The concaves B and sides of case A I prefer to cast in a single piece, as there is then no liability of leakage of mercury or

metal. Steam may be introduced in any convenient manner, though I prefer to introduce it by means of an inlet-pipe, E, placed at the center of the case, or introduced through one of the bearings F, and said pipe may be extended to the upper end of the case, as shown in Fig. 3, so that the steam will issue at that end of the steam-space and cause the upper trough to be the hottest. Water of condensation escapes at the lower end of the case A by means of a pipe, G, which may be provided with a cock or trap-valve. The cylinders C may be made of wood or metal, as may be most convenient or desirable. They are covered on the outside with some material which will be less harsh and unyielding in its action upon the mercury than iron has been found to be when formed with the necessary inequality of surface to produce the required agitation of the auriferous matters within the troughs. I have found a covering of fibrous material, such as hemp or Manila rope, shown on rollers C, to be effective, though a covering of raw-hide, bristles in tufts, as shown on roller C', or cord composed of copper or other soft-metal wire, shown on roller C'', will be nearly, if not quite, as good. The diameter of the cylinders C is such that, when covered as described and shown, there will be a clear space intervening between said cylinder and its trough of about one-fourth of one inch, so that but a small quantity of auriferous matter will be subjected at any one time to the action of the agitating-cylinders, and thereby a much more complete amalgamation is effected than is possible when larger masses are subjected to action at one time. When a mass of auriferous earthy matter mixed with mercury is subjected to the action of a mass of iron moving in close proximity to another mass of iron, the mercury is reduced to the condition called flour by the metallurgists; it is also said to be sickened, or rendered incapable of combining with the precious ore. These effects are neither of them produced with my machine, having cylinders covered with some material less rigid than iron, as rope, raw-hide, &c. The principal mass of the mercury will collect at the lowest part of the concave B, and the corrugations on the surface of the cylinder will continually cause the particles of the ore to be brought in contact therewith. Heretofore,

when revolving cylinders have been employed in connection with a series of concave troughs so that a continuous passage of the auriferous earth from one trough to another was effected, the cylinders were caused to revolve in the direction of the flow from one trough to another, and the passage of the auriferous matter was thereby facilitated; but the result was not beneficial, because the amalgamation of the mercury and metals requires time; and I therefore cause the cylinders C to revolve in a direction contrary to the flow, which is thereby retarded to such an extent as may be necessary to insure complete action with the least number of cylinders. The case A is placed upon an adjustable frame, H, which I prefer to hang upon bearings F, at its center, so that the whole will be balanced, though, if the apparatus is very large, it may be more advantageous to place the bearings at or near one end, and adjust by means of a screw or other device at the opposite end. The frame H, having its bearings placed at its center, may be placed level, or at any desired angle, and it may be secured in the required position by any convenient means. I show an arc, I, and setscrew J for that purpose. The greater the inclination of the case A and frame H, the more rapid will be the passage of the auriferous matters from one trough to another. This is called continuous working, but it sometimes happens that it is desirable to work by charges, and it is then made level, and a certain quantity of auriferous earth is placed in the machine, and the action of the cylinders is continued until all of the ore contained in the charge is amalgamated. When the mercury placed at one time in the troughs has absorbed all of the metal it is capable of holding, it is necessary to stop the machine and discharge the contents. To do this readily requires the removal of the cylinders. When this has been arranged, I find it of great advantage to oscillate or rock the case A upon the bearings of the frame H until the mercury is collected together at the bottom of the trough. The contents of the troughs may then be discharged through a gate, K, at the end of the concave. The journals or bearings of the cylinders C are placed in wedge-shaped slides L, fitted in corresponding seats cut in the sides of the case A. By making the slides wedge-shaped, as shown, they may be easily rendered watertight in their seats, and the journals may pass through stuffing-boxes, to prevent any escape of water from the machine through the journal-boxes. This or some equivalent method of mounting the cylinders is required to permit the ready removal of the cylinders from the machine when its contents are to be discharged. At the outer end of each cylinder-journal, on one side of the machine, is a bevel-pinion, M, which meshes with a corresponding pinion, N, on the driving-shaft O, which is hung in brackets along the side of the case A. I find it convenient to apply the prime motion to one of the cylinders and transmit the mo-

tion from said cylinder to the remaining cylinders, through the intervention of the shaft O and bevel-pinions M N. When the cylinders C are to be removed from the machine, all of the pinions M N are thrown out of gear by moving the shaft O endwise in its hangers. Power is applied to the pulley P, whose axis is coincident with the axis of the bearings F, and from said pulley P a belt, Q, transmits the motion to one of the cylinders C. In order to facilitate the removal of the cylinders and the discharge of the contents of the troughs, I employ a frame, R, which may be as large as the whole case A on its upper edge, or only equal to the length and breadth of a single section thereof; and to said frame I secure all of the slides L, so that when said frame is elevated it withdraws all of the cylinders with it. If the machine is of small dimensions, this may be effected by the strength of two men; but if it is of large dimensions, then it will be more convenient to provide hoisting-machinery, which may consist of a derrick, or of a simple block and tackle suspended from some framework overhead. For the convenient attachment of hoisting-machinery, the eye-bolts S may be inserted in the frame R at such points as may be required.

The machine is located near the stamp-battery, and the auriferous sand and earth is received in a hopper, T, located at the upper end of case A.

Having described my invention, what I claim as new is—

1. In combination with the amalgamator-case A, provided with concaves or troughs B, the cylinders C, covered with some fibrous or equivalent material, substantially as set forth.
2. In combination with the amalgamator-case A, provided with the concaves or troughs B, the cylinders C, arranged and geared to revolve therein in a direction opposite to the flow through the machine, as set forth.
3. Amalgamator-case mounted upon a frame, H, or its equivalent, to make said case adjustable in reference to a horizontal plane.
4. In combination with the amalgamator-case A, provided with troughs B, the cylinders C mounted in wedge-shaped boxes L, constructed, as described, to be easily removable from said case, for the purpose set forth.
5. In combination with the amalgamator-case A, provided with concave troughs B and cylinders C, arranged to revolve therein, the bevel-gears M N, and the sliding shaft O, for the purpose substantially as set forth.
6. In combination with the case A, provided with concaves or troughs B, and the cylinders C mounted in movable boxes L, the connecting-frame R, whereby all of the cylinders may be removed at one operation, substantially as described.
